UNITED STATES PATENT OFFICE

JEAN LÉON REUTTER, OF PARIS, FRANCE

DEVICE FOR AUTOMATICALLY RE-WINDING CLOCKS OR OTHER MECHANISMS BY
THE VARIATIONS OF THE ATMOSPHERIC TEMPERATURE

Application filed May 24, 1929, Serial No. 365,754, and in France November 28, 1928.

The present invention relates to a device for automatic winding of clocks or other mechanisms and more particularly to an automatic device of that type which utilizes 5 the temperature variations of the surrounding atmosphere.

Devices are already known which utilize the pressure differences of the saturated vapor of a liquid or liquefied gas. Such devices have one container immediately responsive to temperature variations and a second container which is maintained at a substantially constant or slowly variable temperature.

15 The difference in temperature between the aforementioned two containers is utilized to produce, by virtue of the ensuing pressure difference, a displacement of a certain mass of liquid, such as mercury, separating both containers and contained in a tube or the like connecting said containers. The displacement of said mass causes an unbalanced condition of the device and consequently rotation about an axis to a condition of equilibrium with the transformation of energy.

20 The present invention has for its object the provision of a device which is free of certain disadvantageous features present in the known devices. According to the invention 25 the container which is maintained at a substantially constant or very slowly variable temperature is entirely surrounded by a chamber of constant or slowly variable temperature, such as a Dewar tube or the like.

30 The interior volume of each of the containers is limited at the bottom by the free surface of the mercury which partially fills the U-tube. The container with the saturated vapor to be kept at a substantially constant or very 40 slowly variable temperature, may be preferably in thermal contact with a body having high specific heat and placed in a thermally isolated chamber (Dewar tube or the like). 45 This body may however be replaced by any substance which, by the physical or chemical changes that it can undergo, may be able to absorb or to restitute a great amount of heat without undergoing a substantial variation 50 of temperature. The other container may be

such that its temperature will quickly change with that of the surrounding air.

The apparatus has thus a very simple construction and, as a further advantage, allows inversion of the apparatus without inconvenience, the mass of mercury automatically returning to its working position when the apparatus is replaced in the upright position, which is not possible with the apparatus known hitherto.

55 The accompanying drawing forming part hereof diagrammatically illustrates devices based on the principles of my invention.

60 Figure 1 shows an example of such a device in which the energy is produced by the displacement of a mass of mercury and also utilized in a practical manner.

65 Figures 2 and 3, on a smaller scale, show the same device in different operative positions.

70 Figure 4 is a modification of the device.

75 Figure 5 is a vertical section of the device of Figure 4 on line 5—5.

Throughout the views, the same reference indicia refer to the same or corresponding parts.

80 In the practice of my invention, as shown in Figure 1 a thermally insulated tube or container 1 of the Dewar tube type, contains a substance 2 such as water, of high specific heat, and in which a branch 3^a of a U-shaped tube 3 is immersed. This tube contains a certain amount of mercury 4 and a liquid or liquefied gas 5, such as ammonia or carbonic acid, with its saturated vapor indicated 85 at 6. The other branch 3^b of the U-shaped tube is exposed to the atmospheric air. All these elements form a unit capable of rotating about an axis X.

85 The working of the device is as follows: 90 If it is supposed that the temperature of the substance 2 is equal to the temperature of the surrounding air the pressure of vapor in both branches 3^a and 3^b is the same and the system is in equilibrium. But if a variation of the temperature of the air occurs (an increase, for instance), the temperature and pressure in the branch 3^b, will rise whilst owing to the high specific heat of substance 2 and the vacuum between casings 7 and 8, 100

the temperature and pressure remains substantially constant in the branch 3^a. The difference of pressure will cause the mercury 4 to be driven from 3^b to 3^a, thus producing an unbalanced condition which causes a clockwise rotation of the unit about the axis X (Fig. 2). Such a movement may be transmitted to the energy storing means of a clock or the like. A lug 10 is mounted on the tube 1 and pivotally connected to a pawl 11 which engages the ratchet wheel 12 actuating the energy storing means (not shown). The pawl 13 also engages the ratchet wheel 12 and prevents counterclockwise movement thereof.

When the temperature of the surrounding air decreases, the mercury 4 is driven back for the same reasons in the branch 3^b and the oscillating movement takes place in a counterclockwise direction (Fig. 3).

In Figs. 4 and 5 is shown a modification of Fig. 1 in which a casing 8 containing the substance 2 of high specific heat is enclosed in a larger casing 7. Between the casings 7 and 8 is provided a thermal isolating medium, for instance, a vacuum. The space also comprises the U-shaped tube the branches of which are especially shaped in order to insure the contact of the branch 3^b with the external casing 7 and the branch 3^a with the internal casing 8. Both branches are preferably connected by a capillary tube 3. The working is similar to that of Fig. 1 and the oscillation is caused about the axis X'.

Manifestly, variations may be resorted to and parts used without others.

Having now fully described my invention, I claim:

1. In an apparatus of the character described, the combination with a U tube including a pair of spaced interconnected branches, and a mass of mercury disposed within said U tube and normally extending a distance into both said branches, of a pivotally mounted container of slowly varying temperature supporting one branch of said U tube, a liquefied gas together with its saturated vapor disposed in each branch of said tube above the level of the mercury therein, and a mass of material of high specific heat arranged within said container in heat exchange contact with said one branch of said tube and extending above and below the general level of the mercury in said branch, the other branch of the U tube being exposed in thermal contact with the atmosphere.

2. In an apparatus of the character described, the combination with a U tube including a pair of spaced interconnected branches, and a mass of mercury disposed within said U tube and normally extending a distance into both said branches, of a pivotally mounted container of slowly varying temperature rigid with one branch of said U tube, a liquefied gas together with its saturated vapor disposed in each branch of said tube

above the level of the mercury therein, and a mass of material of high specific heat arranged within said container in heat exchange contact with said one branch of said tube, the other branch of the U tube being exposed in thermal contact with the atmosphere.

3. In an apparatus of the character described, the combination with a U tube including a pair of spaced interconnected branches, and a mass of mercury disposed within said U tube and normally extending a distance into both said branches, of a pivotally mounted container of slowly varying temperature arranged adjacent to one branch of said U tube, a liquefied gas together with its saturated vapor disposed in each branch of said tube above the level of the mercury therein, and a mass of material of high specific heat arranged within said container in heat exchange relation with said one branch of said tube and extending above and below the general level of the mercury in said branch, the other branch of the U tube being exposed in thermal contact with the atmosphere.

4. In an apparatus of the character described, a pivoted unit for utilizing atmospheric temperature changes, comprising the combination with a U tube including a pair of spaced interconnected branches, and a mass of mercury disposed within said U tube and normally extending a distance into both said branches, of a container of slowly varying temperature enveloping one branch of said U tube, a liquefied gas together with its saturated vapor disposed in each branch of said tube above the level of the mercury therein, and a mass of material of high specific heat arranged within said container in heat exchange contact with said one branch of said tube and extending above and below the general level of the mercury in said branch, the other branch of the U tube being exposed in thermal contact with the atmosphere.

5. In an apparatus of the character described, the combination with a U tube including a pair of spaced interconnected branches, and a mass of mercury disposed within said U tube and normally extending a distance into both said branches, of a container of slowly varying temperature arranged adjacent to one branch of said U tube, a liquefied gas together with its saturated vapor disposed in each branch of said tube above the level of the mercury therein, and a mass of material of high specific heat arranged within said container in heat exchange relation with said one branch of said tube and extending above and below the general level of the mercury in said branch, the other branch of the U tube being exposed in thermal contact with the atmosphere.

6. In an apparatus of the character described, the combination with a U tube in-

cluding a pair of spaced interconnected branches, and a mass of mercury disposed within said U tube and normally extending a distance into both said branches whereby to provide two distinct levels of mercury with 5 one level thereof in each branch, of a container of slowly varying temperature enveloping a portion including the upper end of one branch of said U tube, a liquefied gas, together with its saturated vapor disposed in 10 each branch of said tube above the level of the mercury therein, and a mass of material of high specific heat arranged within said container and also enveloping said portion and upper end of said one branch of said 15 tube in order to be disposed in heat exchange relation with said branch and extending above and below the general level of the mercury in said branch, the other branch of the U tube being exposed in thermal contact with 20 the atmosphere.

In testimony whereof I have affixed my signature.
